(57) **CLAIM**

We claim the ornamental design for an extruded escutcheon,
as shown and described.

DESCRIPTION

FIG. 1 is a perspective view of the claimed design;
FIG. 2 is a front view of the claimed design shown in FIG.

1;

FIG. 3 is a rear view of the claimed design shown in FIG.
1;

FIG. 4 is a side view of the claimed design shown in FIG.
1;

FIG. 5 is another side view of the claimed design shown in
FIG. 1;

FIG. 6 is a top view of the claimed design shown in FIG. 1;
and,

FIG. 7 is a bottom view of the claimed design shown in FIG.
1.

The ornamental design that is claimed is shown in the
drawings as solid lines and surfaces having surface shading.
